Des. 181,375
Patented Nov. 5, 1957

181,375

ELECTRICAL SOCKET

Donald J. Smith, Alexandria, Va., assignor to Sylvania
Electric Products Inc., a corporation of Massachusetts

Application April 20, 1956, Serial No. 41,149

Term of patent 14 years

(Cl. D26—1)

FIG-1

FIG-2

FIG-3

FIG-4

Fig. 1 is a top plan view of an electrical socket embodying my new design.

Fig. 2 is a side elevational view thereof.

Fig. 3 is a bottom plan view of the socket, and

Fig. 4 is a bottom perspective view of the socket.

I claim:

The ornamental design for an electrical socket, as shown.
